TENSIOMETER CONTROL SYSTEM

Gerhard P. Lessmann, Forest Hills, Pa., assignor to Westinghouse Electric & Manufacturing Company, East Pittsburgh, Pa., a corporation of Pennsylvania

Application March 21, 1939, Serial No. 263,146

13 Claims. (Cl. 80—35)

My invention relates, generally, to tensiometer control systems, and more particularly, to systems for controlling the tension on a strip of material as it is passed through a strip rolling mill.

In the operation of steel strip rolling mills it has been found desirable to subject the strip to both front and back tensions at the roll stands. This tensioning of the strip as it is being rolled provides a greater reduction of the strip at each roll stand and thus requires fewer roll stands or reducing passes for a given strip reduction. Rolling the strip under tension also imparts certain desirable characteristics to the strip.

In rolling steel strip under tension, it has been found that the amount of reduction of the strip for a given strip hardness and a given roll setting is a function of the amount of tension to which the strip is subjected. It follows therefore that a strip of varying thickness and hardness may be reduced to a uniform thickness with a given roll setting if the tension is varied in accordance with variations in thickness and hardness of the strip to thus vary the reducing forces in accordance with variations in the resistance-to-reduction of the strip.

An object of my invention is to provide a tensiometer control system which shall function to subject a strip of material, as it passes through a strip rolling mill, to such tensions as will enable the mill to produce strip of uniform thickness.

Another object of my invention is to provide a strip tension control system for a strip rolling mill which shall function to vary the strip tension in accordance with variations in the resistance-to-reduction characteristics of the strip.

Another object of the invention is to provide a tensioning system for a tandem strip rolling mill which shall function to subject a strip to tension as it extends between adjacent roll stands of the mill, vary the strip tension in accordance with variations in the amount of strip between the roll stands, automatically maintain a predetermined amount of strip between the roll stands and vary the amount of strip between the roll stands in accordance with variations in thickness of the strip.

A further object of the invention is to provide a tensioning system for a strip rolling mill which shall function to subject a strip to tension as it extends between a roll stand and another work device, vary the strip tension in accordance with variations in the amount of strip between the roll stand and the work device, automatically maintain a predetermined amount of strip be-

tween the roll stand and the work device, vary the amount of strip between the roll stand and the work device in accordance with variations in the strip thickness and vary the load on the roll stand in accordance with variations in the strip thickness.

Another object of the invention is to provide a tensioning system for a strip rolling mill which shall be simple in construction, simple and efficient in operation, and inexpensive to manufacture, install and maintain.

These and other objects and advantages of the invention will be apparent from the following detailed description taken in connection with the accompanying drawings in which:

Figure 1 is a diagrammatic view of a tension control system for a strip rolling mill embodying the principal features of my invention; and,

Fig. 2 is a diagrammatic view of another embodiment of my invention.

In carrying out my invention, in the embodiment of Figure 1, I provide a tensioning device 10 disposed to bear upon the strip 12 and subject it to tension by deflecting it from its normal pass line between the preceding and succeeding roll stands 14 and 16, respectively. The tensioning device 10 has a rising tension-deflection characteristic, that is, it subjects the strip to tensions which are inverse functions of the strip deflection.

A regulator 18 functions in response to movements of the tensioning device 10 to control the speed of the drive motor 20 of the roll stand 16 to maintain the strip deflection within a predetermined range. A strip thickness responsive device 22 functions to adjust the regulator 18 to vary the limits of variations of strip tension in accordance with variations in strip thickness.

The embodiment of the invention of Fig. 2 is similar to that of Fig. 1 with the exception that a current regulator 24 is embodied therein for controlling the loading of the roll motor 20, and the setting of the current regulator is made responsive to the strip thickness.

Referring again to Fig. 1 for a more detailed description of the principal features of the invention, the tensioning device 10 is constructed and functions in substantially the same manner as the tensioning device of my copending application Serial No. 218,316, filed July 9, 1938, now Patent No. 2,215,329, to which reference is made for a detailed description of its operation. The tensioning device 10 comprises, generally, a tensioning roller 26 mounted on an arm 28 of a

crank 29 having a pivotal mounting 30. The roller 26 is disposed to engage the strip 12 and subject it to tension by deflecting it from its normal pass line between the roll stands 14 and 16 by a fluid pressure operated cylinder and piston 32 which acts upon an arm 34 of the crank 29.

An automatic pressure regulating valve 36 functions to maintain the desired operating pressure on the piston within the cylinder 32 and a cam 38 mounted for operation by the crank 29 operates through the stem 40 to adjust the valve 36 so that the tensioning device will have an increasing tension deflection characteristic. That is, the tension on the strip 12 will increase with decreased deflection of the strip and decrease with increased deflection of the strip. The motor 42 is provided for selectively setting the cam 38 with respect to the operating crank 29 to provide different ranges of tension variation for any given range of strip deflection. This general operation of the tension device 10 is fully set forth in my patent referred to hereinbefore.

The regulator 18 functions to vary the current in the field winding 44 of the drive motor 20 for the roll stand 16. The regulator 18 comprises spaced contact elements 46 and 48 mounted upon an arm 50 which is mounted for movement with the crank 29. A contact element 52 is mounted for movement between the contact elements 46 and 48 upon an arm 53 of a bell crank 54 which has a pivotal mounting 55 and an arm 56 which is actuated against the bias of a spring 57 by a solenoid 58.

A circuit is provided for intermittently increasing and decreasing the energization of the solenoid 58 to cause its armature to reciprocate the arm 56. The energizing circuit for the winding of the solenoid 58 extends from one side of a source of current indicated by conductor A through conductors 60, 62 and 64, the winding of the solenoid 58, conductor 66, resistor 68 and conductor 70 to the other side of the source of current indicated by the conductor B. A shunting circuit is provided for the resistor 68 which comprises the contact element 72 of a relay 74 and conductors 76 and 78. An energizing circuit is provided for the winding of the relay 74 which extends from the conductor A through the conductors 60 and 62, the contact element 80 of the solenoid 58, conductor 82, the winding of the relay 74 and conductors 78 and 76 to the conductor B.

It will be seen that this interconnection of the solenoid 58 and the relays 74 will cause intermittent increases and decreases of energization of the solenoid 58. In the position in which the elements of these circuits are shown, the winding of the solenoid 58 will have full energization and solenoid 58 will actuate its armature to the right moving the contact element 80 to closed circuit position. With the contact element 80 in the closed circuit position, the energizing circuit of the winding of the relay 74 hereinbefore described will be closed and the energization of relay 74 will cause it to move its contact element 72 to open circuit position. With the contact element 72 in open circuit position, the shunting circuit will be removed from the resistor 68 and this will cause decreased energization of the solenoid 58 and will permit the spring 57 to move the armature of the solenoid 58 to the left. The movement of this armature of the solenoid 58 to the left will cause the contact ele-

ment 80 to be moved to the open circuit position, deenergizing the winding of the relay 74 and causing the contact element 72 to be moved to the closed circuit position, thus again starting the cycle of intermittent increased and decreased energization of the winding of the solenoid 58.

The intermittent engagement of the contact element 52 with the contact element 46 caused by the reciprocation of the armature of the solenoid 58 will cause intermittent energization of the winding of a relay 84 through a circuit which extends from the conductor A through the conductor 60, the arm 53, contact elements 52 and 46, conductor 86, the winding of the relay 84, conductors 88, 90, 92 and 70 to the conductor B. In a similar manner, the intermittent engagement of the contact element 52 with the contact element 48 will cause intermittent energization of a relay 94 through a circuit which extends from the conductor A through the conductor 60, the arm 53, contact elements 52 and 48, conductor 96, the winding of relay 94 and conductors 90, 92, and 70 to the conductor B.

The intermittent energization of the relay 84 will cause intermittent movement of its contact element 98 to closed circuit position in a shunting circuit for a resistor 100, the shunting circuit comprising a conductor 102 connected to one side of the resistor 100, the contact element 98 and conductors 104 and 106 to the other side of the resistor 100. Similarly, the intermittent energization of the relay 94 will cause intermittent movement of its contact element 108 from closed circuit position in a shunting circuit for a resistor 110, the shunting circuit comprising the conductors 106 and 104, the contact element 108 and the conductor 112 connected to the resistor 110.

The resistors 100 and 110 are connected in series circuit relation with the field winding 44 of the drive motor 20 through a circuit which extends from the conductor B, through conductors 70 and 92, the resistors 110 and 100, conductor 114, variable resistor 116, conductor 118, the field winding 44, conductor 120 and conductor 60 to the conductor A.

In the operation of the regulator 18, it will be understood that the contact element 52 will alternately engage the contact elements 46 and 48 to intermittently energize the relays 84 and 94 to thus intermittently increase and decrease the current flow in the field winding 44 of motor 20. If, because of increased deflection of the strip 12 by the tensioning device 10, the contact elements 46 and 48 are shifted upward so that in the alternate engagement of the contact element 52 with the contact elements 46 and 48 the contact element 52 will remain in engagement with the contact element 48 longer than the contact element 46, this will result in a longer net energization of the relay 94 than the relay 84, thus producing a net decrease in the energization of the field winding 44 and thus a net decrease in the excitation of the motor 20. This decrease in the excitation of the motor 20 will tend to increase the speed of the motor 20 and the speed of the rolls of the roll stand 16 to take up the slack in the strip 12 and decrease the deflection of the strip. When the deflection of the strip has been decreased, the contact elements 46 and 48 will again assume a normal position with respect to the moving contact element 52 and such a net energization of the field winding 44 will be established.

as will maintain this normal deflection of the strip 12.

Since the tension applied to the strip 12 by the tensioning device 10 is a function of the deflection of the strip 12, automatic variation of the tension on the strip may be obtained by adjusting the regulator 18 to vary the deflection of the strip and to maintain a different degree of deflection of the strip. It will be understood that since the amount of reduction of the strip is a function of the tension applied to it, the amount of reduction of the strip may be decreased by decreasing this tension, and provision is made whereby the thickness responsive device will control the tension applied to the strip, decreasing the tension when the thickness is decreased, and increasing the tension when the thickness is increased, thus automatically providing the proper tension to produce a strip of substantially uniform thickness.

The thickness responsive device 22 comprises contact rollers 122 and 124 mounted for engagement on opposite sides of the strip and connected in a Wheatstone bridge circuit 126 in such a manner as to vary the unbalance of the bridge 126 an amount depending upon the resistance between the rollers 122 and 124 which will vary with the thickness of the strip 12. A solenoid 128 is connected in circuit with the bridge 126 so as to be responsive to the degree of unbalance of the bridge 126. The solenoid 128 actuates the arm 130 of a bell crank 132 having a fixed pivotal mounting 134 and another arm 136, which supports the pivotal mounting 55 for the bell crank 54 hereinbefore described. The solenoid 128 actuates its armature against the biasing tension of a spring 135. Thus it will be seen that the position of the pivotal mounting 55 will be determined by the thickness of the strip 12, and the connections of the solenoid 128 with the Wheatstone bridge 126 are such as to raise the pivotal mounting 55 when the thickness of the strip decreases, and to lower it when the strip thickness increases. Raising of the pivotal mounting 55 will raise the range of movement of the movable contact element 52, and since the range of movement of the contact element 52 determines the position at which the regulator 18 maintains the deflection of the strip 12, the decreased thickness of the strip as measured by the thickness responsive device 22 will cause such a readjustment of the regulator 18 as will increase the deflection of the strip 12 and maintain this increased deflection and thus decrease the tension maintained on the strip 12.

In a similar manner, increases in the thickness of the strip 12, as measured by the thickness responsive device 22, will cause the range of deflection of the movable contact element 52 to be lowered, thus decreasing the deflection of the strip 12 and increasing the tension applied to the strip 12.

Thus it will be apparent that, in the operation of the system of Fig. 1, the strip 12 will be subjected to a tension by the tension device 10 as it passes between the roll stands 14 and 16, which will vary inversely with the deflection of the strip 12, and the amount of tension on the strip will be governed by the thickness of the strip as determined by the thickness responsive device 22, which acts to so adjust the regulator 18 as to cause the regulator 18 to control the speed of the drive motor 20 and therefore the

roll stand 16, to maintain a strip deflection which will produce the necessary strip tension corresponding to the strip thickness.

The embodiment of the invention shown in Fig. 2 is generally similar to that of Fig. 1 with the exception that the loading of the drive motor 20 is also controlled by the strip thickness responsive device 22. Like reference characters are applied to the corresponding elements of the systems of Figs. 1 and 2.

It will be understood that the loading of the drive motor 20 will be made up of rolling load, that is, the actual work done by the rolls of the roll stand 16 in reducing the strip as it passes therethrough and the tensioning load, that is, the loading of the motor occasioned by the constant back tension applied to the strip by the tension device 10. Since it is desirable to maintain a substantially constant rolling load on the motor, it will be seen that the total load on the motor will have to be varied in accordance with variations in strip tension if the rolling load is to be maintained constant. The load on the motor 20 is controlled by a constant current regulator 24 which comprises a solenoid 140 whose armature acts against the bias of a spring 142, tending to move a contact element 144 to closed circuit position in a shunting circuit for a resistor 146 which is connected in series circuit relation with the field winding 44 of the drive motor 20. The circuit for the field winding 44 extends from the conductor A through conductors 60 and 148, the variable resistor 116, conductor 150, the field winding 44, conductor 152, resistors 100 and 110, conductor 112, resistor 146 and conductor 154 to the conductor B. The shunting circuit for the resistor 146 controlled by the movable contact element 144 of the solenoid 140 comprises the conductors 112 and 156, the contact element 144 and the conductor 154.

Normally, the constant current regulator 24 will be energized in accordance with the armature current of the motor 20 and when this current increases beyond a predetermined amount the contact element 144 will close the shunting circuit for the resistor 146, thus increasing the excitation of the motor 20, causing it to tend to decrease its speed and thus decreasing its armature current. In this manner the constant current regulator would normally tend to maintain a constant load on the motor 20. The constant current regulator 24, however, is modified to cause its effective current setting to vary in accordance with the thickness of the strip 12 to thus vary the total load on the motor 20 in accordance with variations in tension applied to strip 12.

A circuit is provided to render the coil of the solenoid 140 responsive to the current of the motor 20 and for varying the sensitivity of the current regulator in accordance with the thickness of the strip. This circuit is influenced by the potential drop across a series winding 158 in the armature circuit of the motor 20, which may be either a series field or an interpole winding, and extends from one side of the winding 158 through conductor 160, the coil of the solenoid 140, conductor 162, resistors 164 and 166, conductor 168, variable resistor 170 and conductor 172 connected to the other side of the series winding 158.

The energization of the winding of the solenoid 140 is influenced by the intermittent connection of the resistors 164 and 166 in its circuit in a manner similar to the intermittent connection of the resistors 100 and 110 in the circuit of the

field winding 44 by the regulator 18 as hereinbefore described in connection with Fig. 1. The control of the resistors 164 and 166 comprises movable contact elements 174 and 176 mounted upon the arm 53 of the bell crank 54 and disposed to alternately engage fixed contact elements 178 and 180, respectively. The intermittent engagement of the contact elements 174 and 178 will cause intermittent energization of a relay 182 through a circuit which extends from the conductor A through the conductor 60, the arm 53, contact elements 174 and 178, conductor 184, the coil of the relay 182, and conductors 186 and 70 to the conductor B. Similarly, relay 188 is disposed to be intermittently energized by the intermittent engagement of the contact elements 176 and 180 through a circuit which extends from the conductor A through conductor 60, the arm 53, contact elements 176 and 180, conductor 190, the coil of the relay 188 and conductors 192, 186 and 70 to the conductor B.

The intermittent energization of the relay 182 will cause its movable contact element 194 to intermittently close a shunting circuit for the resistor 166 which extends from one side of the resistor 166 through the conductor 196, the contact element 194, and the conductors 198 and 200 to the other side of the resistor 166. Similarly, intermittent energization of the relay 188 will cause intermittent movement of its movable contact element 202 away from closed circuit position in a shunting circuit for the resistor 164, the shunting circuit extending from one side of the resistor 164 through the conductors 200 and 198, the contact element 202 and the conductor 204 to the other side of the resistor 164.

The movable contact elements 174 and 176 are mounted upon leaf spring members 206 and 208, respectively, so that as the range of movement of the arm 53 is varied by the thickness responsive device 22 as hereinbefore described, the relative periods of engagement of the contact element 174 with the contact element 178 with respect to the engagement of the contact element 176 with the contact element 180 will be varied to thus vary the periods of energization of the relays 182 and 188, thereby varying the net increase or decrease of the current flow in the coil of the solenoid 140 and hence varying the current setting of the current regulator 24. Thus, as the thickness of the strip 12 decreases, the thickness responsive device 22 will adjust the regulator 18 to cause the deflection of the strip to increase and therefore decrease the tension on the strip. With increased deflection on the strip, the pivotal mounting 55 will move upward and therefore the range of movement of the arm 53 will be moved upward. This upward movement of the range of movement of the arm 53 will cause the contact element 174 to engage the contact element 178 longer than the contact element 176 is in engagement with the contact element 180 on each reciprocation of the arm 53. Thus the relative periods of energization of relays 182 and 188 will cause a net decrease in the resistance of the circuit of the winding of the solenoid 140, thus permitting a smaller motor load current to actuate the armature of the solenoid 140 and resulting in a smaller load current on the motor 20.

Similarly, increasing thickness of the strip will require that a higher tension be applied to the strip, and this higher tension will be applied automatically by the tensioning device 10 under control of the strip thickness responsive de-

vice 22 and the extra load current on the motor 20 to supply this extra tensioning load will be automatically produced by the adjustment of the current regulator 24 by the thickness responsive device 22.

It is to be understood that the systems of Figs. 1 and 2 may be applied to either two roll stands as shown and described herein, or one roll stand and either a winding or unwinding reel of a strip mill, and that the systems may be applied to all of the pairs of stands of a tandem mill in which more than a single pair of roll stands is employed. It is to be understood that any suitable tensioning device may be employed for automatically tensioning the strip 12 so long as it has a rising tension-deflection characteristic as herein described. Also, any suitable current regulator which will function in substantially the manner herein described or any suitable thickness responsive device may be employed in place of those described herein.

It will be seen that I have provided strip tension control means for strip rolling mills which will automatically subject the strip to such tensions as will enable the mill to produce a strip of uniform thickness, which will be inexpensive to manufacture, install and maintain, and which will be simple and effective in operation.

In compliance with the requirements of the patent statutes, I have shown and described herein in the preferred embodiments of my invention. It is to be understood, however, that the invention is not limited to the embodiments shown and described herein, but is capable of modification by one skilled in the art, the embodiments herein described being merely illustrative of the principles of my invention.

I claim as my invention.

1. In a system for controlling the tension on a strip of material as it passes between two adjacent work devices, force operated tensioning means for applying such transverse forces to the strip as will cause the strip tension to vary as a function of the amount of deflection of the strip from its normal pass line between the work devices, regulating means responsive to the degree of deflection of the strip for maintaining the strip deflection within a predetermined range, and continuously operating means responsive to the strip thickness for automatically causing said regulating means to vary the range of deflection of the strip in accordance with variations of the strip thickness.

2. In a system for controlling the tension on a length of material, a pair of material reducing units between which the length of material extends as it is being reduced by said reducing units, a bearing member engaging the length of material to deflect it from a normal pass line and thus subject the length of material to tension, force applying means for causing said bearing member to subject the length of material to tensions which are functions of the amount of deflection of the length of material, regulator means for maintaining the deflection of the length of material within a predetermined range, and continuously operating means responsive to resistance-to-rolling characteristics of the length of material for automatically causing said regulator means to vary the limits of the range of deflection of the length of material.

3. In a system for controlling the tension on a length of material as it extends and passes between a pair of reducing units which operate on the material to reduce its sectional area, a bear-

ing member engaging the length of material to deflect it from a normal pass line and thus subject the length of material to tension, force applying means for causing said bearing member to subject the length of material to tensions which are functions of the amount of deflection of the length of material, means including regulator means actuated in accordance with the deflection of the length of material for maintaining the deflection of the length of material within a predetermined range, and continuously operating means responsive to resistance-to-rolling characteristics of the length of material for automatically adjusting the setting of said regulator means to thereby vary the limits of the range of deflection of the length of material to vary the tensions applied thereto in accordance with variations of said characteristics.

4. In a strip tension control system for a tandem strip rolling mill, a bearing member engaging the strip as it extends between adjacent roll stands of the mill to deflect the strip from a normal pass line and thus subject the strip to tension, means applying such forces to said bearing member as to produce strip tensions which vary as an inverse function of the strip deflection, regulator means responsive to the strip deflection and controlling the relative speeds of the rolls of the adjacent roll stands to automatically maintain the strip deflection within a predetermined range, and continuously operating means responsive to resistance-to-rolling characteristics of the strip for automatically adjusting said regulator means to thereby vary the limits of the range of deflection of the strip thereby varying the strip tension in accordance with variations in said resistance-to-rolling characteristics of the strip.

5. In a strip tension control system for a tandem strip rolling mill, a bearing member engaging the strip as it extends between adjacent roll stands of the mill to subject the strip to tension by deflecting the strip from a normal pass line, actuating means for applying such forces to said bearing member as will produce tensions in the strip which vary as an inverse function of the strip deflection, regulator means responsive to the strip deflection and controlling the relative speeds of the rolls of the adjacent roll stands to maintain the strip deflection within a predetermined range, and means responsive to the resistance-to-rolling characteristics of the strip for adjusting said regulator means to vary the limits of the range of deflection of the strip, thereby varying the strip tension in accordance with variations of the resistance-to-rolling characteristics of the strip.

6. In a system for controlling the tension on a strip of material as it passes between adjacent roll stands of a strip rolling mill, tensioning means for applying such transverse forces to the strip as will cause the tension on the strip to vary as an inverse function of the amount of deflection of the strip from a normal position, means responsive to the degree of deflection of the strip for maintaining the deflection within a predetermined range, means responsive to the resistance-to-reduction of the strip for varying the limits of the range of deflection of the strip, regulating means for maintaining an adjustable substantially constant power input to the succeeding one of the roll stands, and means whereby the value of the power input to the succeeding roll stands is adjusted by said means responsive to the resistance-to-reduction of the strip.

7. In a strip rolling mill having adjacent sets of electric motor driven rolls between which the strip extends as it passes through the mill, a bearing member engaging the strip between the sets of rolls to deflect the strip from a normal pass line and thus subject the strip to tension, means applying such forces to said bearing member as to produce strip tensions which vary as an inverse function of the strip deflection, regulator means responsive to the strip deflection and controlling the relative speeds of the driving motors of the adjacent sets of rolls to maintain the strip deflection within a predetermined range, gauge means responsive to the thickness of the strip for adjusting said regulator means to vary the limits of the range of deflection of the strip, means for maintaining a predetermined load on the driving motor of the succeeding set of rolls, and means whereby said gauge means adjusts the predetermined load value in accordance with variations in the thickness of the strip.

8. In a strip rolling mill having a pair of adjacent sets of electric motor driven reducing rolls between which the strip extends as it passes through the mill, a bearing member engaging the strip between the sets of rolls to deflect the strip from a normal pass line and thus subject the strip to tension, means applying such forces to said bearing member as to produce strip tensions which vary as an inverse function of the strip deflection, regulator means responsive to the strip deflection and controlling the speed of the succeeding roll motor to maintain the strip deflection within a predetermined range, gauge means responsive to the thickness of the strip for adjusting said regulator means to vary the limits of the range of deflection of the strip, current regulator means for maintaining a predetermined load on the succeeding roll motor, and means whereby said gauge means adjusts the predetermined load value in accordance with variations in the strip thickness.

9. In a tension control system for a strip rolling mill, means subjecting the strip to tension as it passes between adjacent roll stands, control means for automatically maintaining a substantially constant load on the succeeding one of a pair of adjacent sets of rolls, regulator means, and continuously operating means responsive to the resistance-to-reduction characteristics of the strip for automatically causing said regulator means to vary the tension on the strip and the load on the succeeding set of rolls in accordance with said resistance-to-reduction.

10. In a tension control system for a strip rolling mill, means subjecting the strip to tension as it passes between adjacent roll stands, load regulator means for automatically maintaining a substantially constant load on the succeeding one of a pair of adjacent sets of rolls, and continuously operating means responsive to the thickness of the strip for automatically varying the tension on the strip and causing the regulator means to vary the load on the succeeding set of rolls in accordance with said thickness.

11. In a tension control system for a strip rolling mill, means subjecting the strip to tension as it passes between adjacent roll stands, load regulator means for automatically maintaining a substantially constant load on the succeeding one of a pair of adjacent sets of rolls, and continuously operating means responsive to the thickness of the strip for automatically causing said regulator means to vary the load on said suc-

ceeding set of rolls in accordance with said thickness.

12. In a control system for a tandem strip rolling mill having an electric drive motor for the succeeding one of a pair of adjacent sets of reducing rolls, tensioning means acting to deflect the strip from a normal pass line and thus subject the strip to tension and operative to subject the strip to tensions which are an inverse function of the deflection of the strip, regulator means responsive to the deflection of the strip and controlling the excitation of the electric drive motor for the succeeding set of rolls to maintain the strip deflection within a predetermined range, and means responsive to the strip thickness for adjusting said regulator means to vary the limits of the range of deflection of the strip in accordance with variations in the thickness of the strip.

13. In a control system for a tandem strip rolling mill having an electric drive motor for the succeeding one of a pair of adjacent sets of reducing rolls, tensioning means acting to deflect

the strip from a normal pass line and thus subject the strip to tension and operative to subject the strip to tensions which are an inverse function of the deflection of the strip, regulator means responsive to the deflection of the strip and controlling the excitation of the electric drive motor for the succeeding set of rolls to maintain the strip deflection within a predetermined range, means responsive to the strip thickness for adjusting said regulator means to vary the limits of the range of deflection of the strip in accordance with variations in the thickness of the strip, current regulator means responsive to the load current of the drive motor for the succeeding set of rolls and operating to vary the excitation of said motor to maintain a substantially constant predetermined load on said motor, and means including said thickness responsive means for varying the value of the predetermined load current of said motor in accordance with variations in the strip thickness.

GERHARD P. LESSMANN.
